UNITED STATES PATENT OFFICE.

EDSON L. BRYANT, OF ANSONIA, CONNECTICUT, ASSIGNOR TO WALLACE & SONS, OF SAME PLACE.

DESIGN FOR A DRAWER-PULL.

SPECIFICATION forming part of Design No. 18,645, dated October 2, 1888.

Application filed September 3, 1888. Serial No. 284,518. Term of patent 7 years.

To all whom it may concern:

Be it known that I, EDSON L. BRYANT, of Ansonia, in the county of New Haven and State of Connecticut, have invented a new Design for a Drawer-Pull; and I do hereby declare the following, when taken in connection with accompanying drawings and the letters of reference marked thereon, to be a full, clear, and exact description of the same, and which said drawings constitute part of this specification, and represent, in—

Figure 1, a front view; Fig. 2, a longitudinal central section.

This invention relates to a design for the handle of drawer-pulls; and it consists in the configuration and ornamentation, as shown in the accompanying illustrations and hereinafter described.

The handle is segment-shaped, gradually contracting in width from the center toward each end, and on the face of the handle is a panel represented as ornamented by a series of angular-shaped facets, as shown.

I claim—

The design for a drawer-pull, consisting in the handle of segment shape, gradually contracting in width from the center toward each end, its face representing a panel ornamented by a series of angular-shaped facets, as shown in the accompanying illustrations.

EDSON L. BRYANT.
